UNITED STATES PATENT OFFICE.

HERBERT FORD WILSON, OF PADDINGTON, ENGLAND.

LIFE-SAVING DEVICE FOR USE IN SUBMARINES.

1,177,372.

Specification of Letters Patent. Patented Mar. 28, 1916.

Application filed February 11, 1915. Serial No. 7,637.

To all whom it may concern:

Be it known that I, HERBERT FORD WILSON, a subject of the King of Great Britain, residing at No. 25 Howley Place, Paddington, in the county of Middlesex, England, have invented certain new and useful Improvements in Life-Saving Devices for Use in Submarines, of which the following is a specification.

10 This invention relates to devices whereby persons may be released from submerged submarine boats when disabled from certain causes of the kind in which a chamber is employed having means of ingress for a 15 person from the interior of the vessel and means of egress to the surrounding water so that the person in the chamber may escape therefrom, means also being provided whereby the water which enters the chamber 20 is removed therefrom to the exterior.

The main object of the said invention is to provide for rapid removal of the water from the chamber and the said invention consists, essentially, in arranging a piston 25 within the said chamber which piston may be reciprocated to cause the water which has entered it to pass from the chamber into the surrounding water.

The said invention is hereinafter particularly described with reference to the accompanying drawings which illustrate a convenient embodiment of the said invention.

Figure 1 of the said drawings is a longitudinal vertical section of a portion of a submarine boat illustrating the aforesaid life saving device partly in section and partly in side view, Fig. 2 is a section taken approximately on the line A—A Fig. 1 looking toward the left of that figure and 40 Fig. 3 is a plan view.

In the following description the parts of the said figures are referred to by the numerals marked thereon the same numerals of reference indicating the same parts in all 45 the figures.

1 is the aforesaid chamber or receptacle secured below the upper part of the body of the submarine boat the said chamber being cylindrical internally and open at one end 2 and closed at the other end by a hinged door 3. Within the chamber 1 a piston 4 is arranged having a piston rod 5 passing through a stuffing box 6 secured to the wall 7 of a recess 8 open at top and communicating with the chamber 1 by its open end 2. The said piston rod 5 is further

supported by the fixed bearing 9 and has secured on a portion of it between the stuffing box 6, and bearing 9 a toothed rack 10. The said piston 4, which is illustrated somewhat diagrammatically, is provided with suitable packing and with non-return spring valves 11, 11. The upper part of the chamber 1 is partly formed of or provided with two doors 12, 13 hinged at 14, 14 to the body 60 of the said chamber and opening outwardly to the exterior of the submarine and when closed completing the internal cylindrical form of the chamber 1. The said doors 12, 13 have overhanging edge parts 15, 15 which when closed abut against the exterior of the adjacent parts of the chamber 1 and the door 13 has an overhanging edge part or lip, 16 which, when the doors 12, 13 are closed abuts against the exterior of the adjacent 70 part of the door 12. The junctions between the doors 3, 12, 13 and the chamber 1 must be watertight or nearly watertight and to this end it is preferable to arrange strips of suitable packing material between the 75 engaging parts of the said doors and the chamber.

In order that the doors 12, 13 may be opened as indicated in broken lines in Fig. 2 recesses 17, 17 are formed in the body of 80 the submarine boat at the sides of the chamber 1 where the doors 12, 13 are arranged. The doors 12, 13 are operated by means of links 18, 18 pivoted at their lower ends to the said doors respectively and having engaged with their upper ends screw nuts 19, 19 engaged respectively with right and left hand screw threads on a rod or shaft 20 mounted in bearings 21, 21. The said shaft 20 is rotatable through toothed gear 90 21 and a shaft 22 and toothed gear 23 by an electric motor 24 within the submarine boat a stuffing box 25 being provided at the part where the shaft 22 passes from the interior to the exterior. The rack 10 on the 100 piston rod 5 meshes with a toothed wheel 26 driven through toothed gear from an electric motor 27. The electric motors 24, 27 are of the reversing type and arrangements of a suitable kind are provided in combination with each of them whereby on the pre-determined or necessary limit of the movement in either direction of the parts operated by them the motor is automatically cut out and free to be made to operate in the 110 reverse direction.

28 is a pipe communicating with the

chamber 1 near its door end and at its other end with a tank within the submarine the said pipe being provided with a valve 29 whereby water may be allowed to flow from the chamber 1 when necessary or desirable as hereinafter referred to.

30 is a spring push piece operable from within the chamber to set in motion the motor 24 for opening the doors 12, 13 as 10 also hereinafter referred to.

31 is an insertion of glass in the wall of the chamber 1 and forming part thereof, for observation use.

The device hereinbefore described is used 15 as follows: The piston 4 and doors 12, 13 are normally in the positions shown in full lines in the accompanying drawings and the valve 29 closed and assuming that the submarine boat is submerged and for some unforeseen reason cannot rise to the surface, in 20 order that the persons imprisoned therein may escape therefrom and rise through the water above, the motor 27 is first set in motion in a direction proper to rotate the toothed wheel 26 so that it operates the toothed rack 10 toward the right hand of Fig. 1 thereby causing the said piston to move in the same direction and clear the body of the chamber 1 from water which on 25 submersion of the submarine boat has entered it through the passage 8 and open end 2 the said motor being automatically stopped by the cut out arrangements hereinbefore referred to when the piston 4 is near the 30 said open end. The person who is to be set free having attired himself in a cork suit or buoyant covering and if necessary with some form of watertight headdress or helmet, then enters the chamber through the 35 opening closed by the door 3 which is then secured or held if necessary against its seat. The other persons within the vessel, then by 40 observation through the glass 31, learning that the person within the chamber 1 is in 45 a proper attitude for release set the motor 24 in action in the proper direction to operate the gears 23, 21^A to rotate the shaft 20 so that the nuts 19, 19 are caused to travel toward the ends of the said shaft and so 50 through the links 18, 18 lift the doors 12, 13 as indicated by the broken lines in Fig. 2 the motor 24 being automatically stopped, when the said doors are in this position by 55 the cut out arrangements hereinbefore referred to. On the opening of the doors 12, 13 water enters the chamber 1 through the opening they normally close but cannot escape materially therefrom into the vessel because the door 3 is closed and is kept 60 tightly on its seat by the water pressure but the person in the water in the chamber rises, or may lift himself through the door opening above him into the surrounding water and is thus free to rise to the surface. When 65 by observation through the glass 31 or by

calculation it is certain that the person previously in the chamber is free from it the motor 27 is set in motion to move the piston 4 back again to the position shown in Fig. 1 the water in front of it passing upwardly 70 between the open doors 12, 13 until the piston passes by them after which the water in front of the piston passes to its rear through the valves 11, 11 in it until the piston is at the end of its stroke which is controlled by the automatic cut out means hereinbefore referred to. The doors are then closed down by operation of the motor 24 and the water remaining in the space in front of the piston may be drained away by 80 opening the valve 29 in the pipe 28 although such water being small in volume compared to the size of the chamber, is not materially prejudicial to the next use of the chamber 1. For releasing the next person the piston 4 is caused to move backward again as before described forcing the greater part of the water behind it through the open end 2 of the chamber 1, into and through the passage 8. A person then enters the chamber, the 90 doors 12, 13 are opened, the person escapes and the piston is caused to move forward and the doors 12, 13 closed in the same manner as in the case of the first person set free. When all the imprisoned persons have left 95 the vessel except one there is no one remaining to control the operation of the motor 24 for opening the doors 12, 13 and therefore after that person has entered the chamber 1 he operates the push piece 30 for setting the 100 motor 24 in action to open the doors.

When the vessel passes beneath the surface of the water during its ordinary evolutions water enters the chamber 1 through the space 8 and if desired provision such as a 105 pump may be made in order that this water may be removed after the vessel has during its evolutions again risen to the surface.

It is preferred to provide a submarine boat with several of the chambers 1 with the 110 operating means in connection therewith as hereinbefore described so that more than one person may be set free at the same time and so that if one device be disabled for any reason, means of escape are still available. 115 The number of the said chambers depends upon the size of the boat and the number of its crew but in the case of a submarine boat of the largest type four may be a convenient number.

By providing for removal of the water from the chamber 1 by actuation of a piston within it the said water may be rapidly and efficiently removed and by arranging it in relation to the means of ingress and egress 125 substantially as hereinbefore described the means of ingress need only be subject to external pressure during the time the piston is removing water from the chamber and a person is entering the same.

What I claim and desire to secure by Letters Patent of the United States is:—

1. A life saving device for use in submarine boats consisting in the combination of a chamber, an ingress thereto for a person to be saved, an egress therefrom to the exterior of the boat for such person, a piston in said chamber and means for reciprocating said piston.
10. 2. A life saving device for use in submarine boats, comprising in combination a chamber, a piston therein, means for reciprocating said piston, an ingress to said chamber for a person to be saved on one side of said piston and capable of closure, a passage for water from said chamber to the exterior of the boat on the other side of said piston and an egress from said chamber to the exterior of the boat for the person to be saved, said egress being in the path of reciprocation of said piston and capable of closure.
15. 3. A life saving device for use in submarine boats comprising in combination a chamber, a piston therein, and ingress to said chamber for a person to be saved, on one side of said piston and capable of closure, a passage for water from said chamber to the exterior of the boat on the other side of said piston, an egress from said chamber to the exterior of the boat for a person to be saved, said egress being in the path of reciprocation of said piston, means for closing said egress adapted when in closed position to form part of the wall of said chamber along which said piston reciprocates, and means to operate said piston in one direction to expel the water that has entered the chamber while the said egress is open and in the other direction after the egress is closed to expel the water that has followed the piston through said passage.
20. 4. A life saving device for use in submarine boats comprising in combination a chamber, an entry door at one end thereof, a piston in said chamber, means for reciprocating said piston an opening at the other end of said chamber communicating with the exterior of the boat and an egress from said chamber for persons to be saved, in the path of said piston.
25. 5. A life saving device for use in submarine boats comprising in combination a cylindrical chamber, an entry door at one end thereof giving access to the interior of said chamber from the interior of the boat, a piston within said chamber, means to reciprocate said piston, a communication between the other end of said chamber and the exterior of the boat, hinged exit doors in the wall of said chamber forming when closed a continuation of the internal surface of the said chamber and in the path of reciprocation thereof, a window in the wall of the said chamber, and means operable within the said chamber for controlling the operation of said piston and the opening and closing of the egress for the person to be saved.
30. 6. A life saving device for use in submarine boats comprising in combination a chamber, an ingress thereto for a person to be saved, an egress therefrom to the exterior of the boat for such person, a piston in said chamber, means for reciprocating said piston, and a window in the wall of the chamber.
35. 7. A life saving device for use in submarine boats comprising in combination a chamber, an ingress thereto for a person to be saved, an egress therefrom to the exterior of the boat for such person, a piston in said chamber, means for reciprocating said piston, and non-return valves in said piston.
40. 8. A life saving device for use in submarine boats comprising in combination a chamber, an ingress thereto for a person to be saved, an egress therefrom to the exterior of the boat for such person, a piston in said chamber, means for reciprocating said piston, and means operable within the chamber for controlling the operation of said piston and the opening and closing of the egress for the person to be saved.
45. 9. A life saving device for use in submarine boats comprising in combination a cylindrical chamber, an entry door at one end thereof giving access to the interior of said chamber from the interior of the boat, a piston within said chamber, means to reciprocate said piston, a communication between the other end of said chamber and the exterior of the boat, hinged exit doors in the wall of said chamber forming when closed a continuation of the internal surface of the said chamber and in the path of reciprocation thereof, a window in the wall of the said chamber, and means operable within the said chamber for controlling the operation of said piston and the opening and closing of the egress for the person to be saved.

In testimony whereof I affix my signature in presence of two witnesses.

HERBERT FORD WILSON.
